UNITED STATES PATENT OFFICE.

FREDERIC MORTIMER EMERSON, OF BOSTON, MASSACHUSETTS, ASSIGNOR TO EMERSON & NORRIS CO., OF BOSTON, MASSACHUSETTS, A CORPORATION OF MASSACHUSETTS.

WALL.

1,034,770.

Specification of Letters Patent.

Patented Aug. 6, 1912.

Application filed November 30, 1909. Serial No. 530,599.

To all whom it may concern:

Be it known that I, FREDERIC MORTIMER EMERSON, a citizen of the United States, residing at Boston, in the county of Suffolk and State of Massachusetts, have invented a new and useful Wall, of which the following is a specification.

This invention relates to a concrete wall and block therefor.

10 It is well understood in this art that an ideal wall for a building should be fire-proof, damp-proof, and non-conductive of heat and cold, and that it should be pleasing in appearance, consisting of true monoliths 15 and of a substance hard, dense, and non-absorbent.

Important objects of this invention are to provide a construction having all of these advantages, and at the same time capable of 20 being constructed without the use of wood or iron forms and at a reduction of cost in laying up; and to provide improved means whereby the whole mass can be bound together in the wall so as to secure the block 25 anchors and the vertical steel reinforcing rods.

Further objects and advantages of the invention will appear hereinafter.

Reference is to be had to the accompanying drawings, in which—Figure 1 is a perspective view showing portions of two courses of a wall in accordance with this invention in the course of construction. Fig. 2 is a perspective view of a block of one of the 35 courses; Fig. 3 is a perspective view of a block of the other course, and Fig. 4 is a plan on reduced scale showing a slight modification.

The invention is shown as embodied in a 40 form of wall having two forms of blocks, both embodying the features of the invention, arranged in alternate courses. The blocks in these two courses are designated 10 and 11 respectively. One of the blocks 10 and 11 respectively. One of the blocks 10 will first be described. This block is shown as comprising a main body of a general rectangular shape in cross section and as having a tongue 12 projecting from the inner face thereof at a short distance from one end. The other end of the block is shown in Fig. 3 as plain. Near the center there is an inward projection 13 the purpose of which will be described later. Extending longitudinally through the block are shown hori-

zontal metallic reinforcing members 14 projecting at one end through the outer side surface of the tongue 12 and projecting from the inner face of the block at a very short distance from the other end. These projecting ends constitute block anchors as 55 60 will appear hereinafter.

Each of the blocks 11 has substantially the same characteristics but in order that the blocks may be laid to break joints the tongues 15 which correspond to the tongues 12 are located just at one side of the center. The blocks also have anchors 140 and inwardly extending projections 16 at their opposite ends, each having a vertical groove 17 in the end thereof which rest upon the 70 projections 13 when the blocks are laid to break joints as indicated in Fig. 1. In both cases it will be seen that the tongues are located between, and spaced from, the center and end of the block.

75 In laying the wall a course of blocks 10 is laid up in the manner indicated in Fig. 1 with the tongues on the front course located at the same end of the blocks and the tongues on the rear course located at the 80 opposite end. Each tongue of course extends into contact with the opposite block. Then a course of blocks 11 is placed on top of the first course breaking joints and with their tongues registering. Consequently, 85 these tongues divide the space between the outer and inner courses of the wall into two sets of alternate spaces 18 and 19. These spaces register with each other in the several courses, and form vertical air spaces 90 and vertical spaces for holding a binding material respectively. The vertical air spaces 18 are free from metallic projections of all kinds, but the anchors 14 and 140 project from opposite ends into the spaces 19 95 and can be connected with each other within these spaces if desired. Through these spaces also pass the vertical steel reinforcing rods 20. When several courses have been built up alternately as indicated in 100 Fig. 1, the vertical spaces which hold the anchors and reinforcing rods are poured full of a liquid concrete grout which hardens and binds the whole mass together, clenching the bolt anchors and the steel 105 reinforcing rods. In this way the tongues perform the office of forms and the necessity of removable forms for holding the binding

grout is avoided, thus economizing both in the materials used and time required in the construction of the wall.

The blocks preferably are cast from wet concrete in sand molds face up, which insures a dense, hard, and non-absorbent block to which a great variety of surface treatments can be applied on the face. Plaster can be applied directly upon the inside face if desired. The blocks are adapted for any thickness of wall, as the thickness is dependent upon the length of the tongues. If an extra thickness of wall is desired, the tongues can be cast so as to project from both inside faces of the opposite blocks to meet either in the center or elsewhere as desired. This is shown in Fig. 4, in which tongues 22 and 23 are shown, one of them being a long one and the other a short one.

While I have illustrated and described a preferred embodiment of the invention I am aware that many modifications can be made therein by any person skilled in the art without departing from the scope of the invention as expressed in the claim. Therefore, I do not wish to be limited to all the details of construction herein shown and described, but

What I do claim is:

In a wall, the combination of alternate

courses of duplicate blocks, each block having a single inwardly extending tongue near, but spaced from, one end, each course being made up of outer and inner blocks, the outer blocks all being arranged with their tongues near one end, and the inner blocks all being arranged with their tongues near the opposite end, the ends of each inner block being directly opposite those of the opposite outer block, each of said tongues extending clear across the space between the blocks and engaging the flat surface of the block on the other side, whereby vertical air spaces are left between the tongues alternating with smaller vertical spaces at the ends of the blocks, and remaining courses located between each two of said alternate courses made up of blocks having corresponding tongues just at one side of the center, each tongue projecting across the space between the blocks and forming alternate spaces as in the alternate courses.

In testimony whereof I have hereunto set my hand, in the presence of two subscribing witnesses.

FREDERIC MORTIMER EMERSON.
